UNITED STATES PATENT OFFICE.

EDWIN W. PIERSON, OF NEWARK, NEW JERSEY, ASSIGNOR TO MERGENTHALER LINOTYPE COMPANY, A CORPORATION OF NEW YORK.

TYPOGRAPHICAL MACHINE.

Application filed July 27, 1922. Serial No. 577,958.

To all whom it may concern:

Be it known that I, EDWIN W. PIERSON, a citizen of the United States, residing at Newark, in the county of Essex and State of New Jersey, have invented certain new and useful Improvements in Typographical Machines, of which the following is a specification, reference being had therein to the accompanying drawing.

- 10 This invention relates to typographical machines, such as linotype machines of the general organization represented in U. S. Letters Patent to O. Mergenthaler No. 436,532, wherein circulating matrices are released from a magazine in the order in which their characters are to appear in print, then assembled in line, the composed line transferred to the face of a slotted mold, the mold filled with molten metal to form a slug 15 or linotype against the matrices which produce the type characters thereon, and the matrices thereafter returned through distributing mechanism to the magazine from which they started. In these machines, the 20 composed line is transferred from the assembling channel or elevator into the casting channel or elevator by means of a horizontally movable carriage comprising a slide or body portion and a pair of line 25 engaging fingers, one short and the other long. The short right-hand finger is fixed to the carriage slide, while the long left-hand finger is loosely mounted with reference thereto, the latter finger being ordinarily 30 provided with a friction device which tends to hold it stationary. As the transfer carriage is thus constructed, the composed line is advanced to the left by the right-hand finger and in its advance picks up the 35 left-hand finger and carries it along therewith, it being understood that the frictional resistance offered to the movement of the left-hand finger is overcome by the power applied to operate the carriage. In the 40 return movement of the carriage, the left-hand finger is restored to the right by the customary adjustable stop on the carriage slide which locates it at the proper distance from the right-hand finger. The loose 45 mounting of the left-hand finger is intended primarily to enable the transfer carriage to accommodate itself to short lines, that is to say, lines shorter than that for which the two fingers are adjusted. Thus, when a short 50 line is delivered to the transfer carriage, the leading matrix of the line necessarily stands some distance away from the left-hand finger, but this distance is immediately taken up during the initial movement of the transfer carriage, due to the fact that the left-hand finger is held at rest until 55 picked up by the advancing line. In this way, the two fingers are caused to approach each other and confine the line between them, 60 reliance being placed upon the above mentioned friction device to maintain the fingers in this condition until the line is taken from the carriage by the casting elevator. It has been found in practise that, notwithstanding 65 the friction device carried thereby, the left-hand finger frequently becomes separated from the line before the latter leaves the transfer carriage, such separation being due for the most part to the jar developed by the abrupt stoppage of the 70 carriage in its delivery position. As a result, the matrices become loose in the line (particularly those at the leading end) and oftentimes drop out or else become so displaced as to interfere with the proper 75 delivery of the line to the casting and other devices, thereby causing damage to the parts 80 and giving rise to other serious objections. 85 The present invention is intended to overcome the foregoing objections and aims to provide an effective guard against the separation of the two line engaging fingers under the conditions stated. To this end, specifically, the left-hand finger is provided, 90 in addition to its customary friction device, with a spring-actuated pawl or detent held in engagement with the usual ratchet teeth on the carriage slide and which acts to lock the left-hand finger against relative movement toward the left or away from the 95 right-hand finger while permitting an initial independent movement of the latter finger in forwarding the line. On the return movement of the transfer carriage, the spring-actuated pawl or detent is automatically disengaged by a suitable trip device on the 100 machine frame so as to permit the left-hand finger to resume its original position. Briefly stated, the arrangement is such that, 105 during the transfer of the line, the two fingers are allowed to approach each other in confining the line between them and are then positively locked against separation until the line is taken away.

In the accompanying drawings, the inven-

tion has been shown merely in preferred form and by way of example and as applied to the particular kind of machine mentioned, but obviously many changes and alterations 5 may be made therein and in its mode of application and still be comprised within its spirit. Generally speaking, the invention is not limited to any specific form or adaptation except in so far as such limitations are 10 specified in the claims.

Referring to the drawings:

Fig. 1 is a front elevation of a portion of a linotype machine equipped with the present improvement;

15 Fig. 2 is a similar view, on an enlarged scale, of the line transfer carriage and associated parts;

Fig. 3 is a plan view thereof, and showing the left-hand finger of the transfer carriage 20 in locked condition;

Fig. 4 is a similar view but showing said finger unlocked; and

Fig. 5 is a transverse section taken on the line 5—5 of Fig. 2, looking toward the right.

25 In the drawings, only those parts of the machine necessary to an understanding of the invention have been illustrated, and it will be understood that the other parts may be of the ordinary or any suitable construction.

The matrices X are released from the magazine A by the manipulation of the keyboard A—1 and drop onto the conveyor belt A—2 which delivers them into the assembling elevator A—3, wherein they are composed in line with the spacers Y. After composition, the elevator A—3 is raised into registration with the intermediate channel C and the composed line then carried there-through into the casting elevator D, which thereupon descends to present the line to the casting and other devices (see the dotted line showing in Fig. 1). The shifting of the composed line from the assembling elevator A—3 to the casting elevator D is effected by means of a so-called transfer carriage comprising the horizontal slide or body portion B and the two line engaging fingers B—1 and B—2. The slide B is mounted in the 40 guideway O—1 of the machine frame O and is moved to and fro by the power-operated lever B—3. The right-hand finger B—1 is rigidly secured to the slide B, whereas the left-hand finger B—2 is loosely mounted with reference thereto, being attached to the 45 separate block B—4 slidably arranged in the guideway O—1 and having the guide rod B—5 passing loosely through an opening in the other finger. The setting of the finger B—2 from the finger B—1 is determined by the adjustable stop B—6 carried by the slide B and which is adapted to abut against the sliding block B—4 in the line receiving position of the transfer carriage (see Fig. 1). 50 The stop B—6 is held in its adjusted position by the pawl B—7 which cooperates with ratchet teeth formed on the front face of the slide B. The finger B—2, or more specifically its sliding block B—4, is provided with a friction device in the form of the spring-pressed plunger B—8 bearing against the smooth face of the machine frame just above the guideway O—1.

55 The foregoing parts and their mode of operation are substantially as shown and described in the Rogers Patent No. 795,936, to which reference may be had if desired. However, it may be noted that, when the transfer carriage is moved to the left for the transfer of the composed line, the left-hand finger B—2 is held at rest by the plunger B—8 until the forward end of the line is carried against it by the advance of the right-hand finger B—1 (compare Figs. 1 and 2). The power applied to advance the 60 carriage is sufficient of course to overcome the frictional resistance of the plunger B—8, and consequently the finger B—2 is carried along by the composed line until the carriage reaches its delivery position, where it is arrested by the engagement of the slide B with the fixed stop O—2 on the machine frame. If (as in Fig. 1) the line forwarded is shorter than the original distance between the two fingers, the left-hand finger B—2 65 will stand out of engagement with its setting stop B—6 at the time of arrest of the transfer carriage (due to the initial independent movement of the slide B), and hence the finger has a tendency to jump or rebound away from the line when the carriage is arrested. Heretofore, the plunger B—8 has been relied upon to resist this tendency of the finger, but in actual practise it is found that the jar developed by the 70 abrupt stoppage of the carriage is great enough to overcome the frictional resistance of the plunger, thereby giving rise to the objections previously noted. According to the present invention, means are provided for 75 positively locking the left-hand finger against movement under the foregoing conditions, as will now be described in detail.

80 In the preferred embodiment illustrated, the means employed consists of a toothed pawl or detent E carried by the sliding block B—4 and normally held in engagement with the ratchet teeth on the slide B by a spring-actuated lever E—1. It will be seen at once that, by reason of this pawl and ratchet arrangement, the finger B—2 is 85 positively locked against movement toward the left relatively to the slide B, although the relative movement of the parts in the opposite direction is freely permitted. It follows, therefore, that when the transfer carriage is moved to the left in forwarding the composed line, the plunger B—8 functions as before to hold the finger B—2 at 90 rest until engaged by the advancing line 95

(the detent E yielding readily to permit such initial independent movement of the slide B), but when the finger is picked up and carried along by the advancing line, such relative movement of the parts immediately ceases, and the detent E then acts to lock the finger in its new position to the carriage slide (Fig. 3). This condition obtains throughout the remainder of the transfer movement of the carriage and in fact until the composed line is taken from the carriage by the casting elevator, so that any lateral displacement of the left-hand finger before the line is delivered to the casting and other devices is thus positively prevented.

When the transfer carriage is returned to the right for receiving the next line, it is important that the left-hand finger be restored to its original position so as to stand at the proper distance from the right-hand finger, it being obvious that a succeeding line may be longer than the preceding one. For this reason, means are provided for automatically disengaging the detent E from the slide B during the return movement of the carriage. In the present instance, there is employed for the purpose a trip device F located on the machine frame above the guideway O—1 and in the path of travel of the forwardly extending arm of the spring-actuated lever E—1. This trip device has a hinged section F—1 which, during the line-forwarding movement of the transfer carriage, will yield or move out of the way when engaged by the lever (see Figs. 2 and 3), but which, during the return movement of the carriage, will serve as a rigid abutment to engage and operate the lever for the withdrawal of the locking detent (see Fig. 4). When the pawl is thus withdrawn, the finger B—2 is immediately brought to rest by the spring-pressed plunger B—8 and remains so until engaged or picked up by the stop B—6 (see dotted lines Fig. 4), which then carries it back to its original position.

As previously stated, the invention has been shown only in preferred form and by way of example and as applied to the particular type of transfer carriage noted, but obviously many changes and alterations in the various parts and in their mode of application will readily suggest themselves to those skilled in the art without departing from the spirit of the invention.

Having thus described my invention, its construction and mode of operation, what I claim is as follows:

1. In a typographical machine, the combination with a movable line transfer carriage having two fingers to engage the line at opposite ends, of means mounted on the carriage and acting during the transfer movement thereof to permit the two fingers to approach each other in confining the line

between them and thereafter to lock the fingers against separation.

2. In a typographical machine, the combination with a movable line transfer carriage having two fingers to engage the line at opposite ends, of means mounted on the carriage and acting during the transfer movement thereof to permit the two fingers to approach each other in confining the line between them and thereafter to lock the fingers against separation, and means acting automatically on the return movement of the carriage to release the fingers and allow them to be restored to their original condition.

3. In a typographical machine, the combination with a movable line transfer carriage comprising a finger to advance the line and a loosely mounted finger arranged to be engaged by the advancing line and carried along therewith, of a locking detent associated with the loosely mounted finger and acting to prevent its separation from the line after its engagement therewith.

4. In a typographical machine, the combination with a movable line transfer carriage comprising a finger to advance the line and a loosely mounted finger arranged to be engaged by the advancing line and carried along therewith, of a locking detent associated with the loosely mounted finger and acting to prevent its separation from the line after its engagement therewith, and automatic means for tripping the locking detent on the return movement of the carriage to permit the resetting of the loosely mounted finger.

5. In a typographical machine, the combination with a movable line transfer carriage comprising a slide and a pair of line engaging fingers, one fixed to the slide and the other loosely mounted with reference thereto, of a locking detent carried by the loosely mounted finger and cooperating with the slide to prevent the separation of the two fingers while permitting them to approach each other during the transfer movement of the carriage.

6. In a typographical machine, the combination with a movable line transfer carriage comprising a slide and a pair of line engaging fingers, one fixed to the slide and the other loosely mounted with reference thereto, of a locking detent carried by the loosely mounted finger and cooperating with the slide to prevent the separation of the two fingers while permitting them to approach each other during the transfer movement of the carriage, and a trip device mounted on the machine frame in position to disengage the detent from the slide during the return movement of the carriage so as to allow the two fingers to be restored to their original condition.

7. In a typographical machine, the com-

4
bination with a movable line transfer carriage comprising a slide and a pair of line engaging fingers, one fixed to the slide and the other loosely mounted with reference thereto, of a friction device carried by the loosely mounted finger and bearing against the machine frame to resist movement of the finger in either direction, and a detent also carried by the loosely mounted finger and cooperating with the slide to lock said finger positively against relative movement away from the fixed finger.

8. In a typographical machine, the combination with a movable line transfer carriage comprising a slide, a pair of line engaging fingers, one fixed to the slide and the other loosely mounted with reference thereto, and an adjustable stop mounted on the slide for setting the loosely mounted finger at the proper distance from the fixed finger, of a friction device carried by the loosely mounted finger and bearing against the machine frame to resist movement of the finger in either direction, and a detent also carried by the loosely mounted finger and cooperating with the slide to lock said finger against relative movement in the direction of the stop.

9. In a typographical machine, the combination with a movable line transfer carriage comprising a slide, a pair of line engaging fingers, one fixed to the slide and the other loosely mounted with reference thereto, and an adjustable stop mounted on the slide for setting the loosely mounted finger at the proper distance from the fixed finger, of a friction device carried by the loosely mounted finger and bearing against the machine frame to resist movement of the finger in either direction, a detent also carried by the loosely mounted finger and cooperating with the slide to lock said finger against relative movement in the direction of the stop during the transfer movement of the carriage, and a trip device mounted on the machine frame in position to disengage the locking detent from the slide on the return movement of the carriage.

10. In a typographical machine, the com-

bination with a line transfer carriage comprising a horizontally movable slide formed with ratchet teeth and a pair of line engaging fingers, one fixed to the slide and the other loosely mounted with reference thereto, of a spring-actuated toothed detent carried by the loosely mounted finger and normally held in engagement with the ratchet teeth on the slide, and a trip device mounted on the machine frame in position to disengage the toothed detent from the slide on the return movement of the carriage.

11. In a typographical machine, the combination with a line transfer carriage comprising a horizontally movable slide formed with ratchet teeth, a pair of line engaging fingers, one fixed to the slide and the other loosely mounted with reference thereto, and an adjustable stop mounted on the slide and normally arranged in engagement with the loosely mounted finger, of a friction device carried by the loosely mounted finger and bearing against the machine frame, a spring-actuated toothed detent also carried by the loosely mounted finger and normally held in engagement with the ratchet teeth on the slide, and a trip device mounted on the machine frame and adapted to disengage the spring-actuated detent from the slide.

12. In a typographical machine, the combination with a line transfer carriage comprising a horizontally movable slide formed with ratchet teeth and a pair of line engaging fingers, one fixed to the slide and the other loosely mounted with reference thereto, of a spring-actuated toothed detent carried by the loosely mounted finger and normally held in engagement with the ratchet teeth on the slide, a pivoted lever also carried by the loosely mounted finger and connected to the spring-actuated detent, and a trip device mounted on the machine frame and having a hinged section arranged in position to be engaged by the lever, all substantially as shown and described.

In testimony whereof I have affixed my signature hereto.

EDWIN W. PIERSON.
